UNITED STATES PATENT OFFICE.

IRWIN WALDSMITH, OF ROCKY FORD, COLORADO.

VENDING MACHINE FOR LIQUID DISPENSERS.

Application filed October 29, 1924. Serial No. 746,456.

To all whom it may concern:

Be it known that IRWIN WALDSMITH, a citizen of the United States, residing at Rocky Ford, in the county of Otero and State of Colorado, has invented certain new and useful Improvements in Vending Machines for Liquid Dispensers, of which the following is a specification.

This invention is in the way of a vending machine for liquid dispensers, but especially for the type of dispenser used by filling stations, and its main object is to provide a coin operated device that can be attached to the air pressure gasoline dispensers that are in common use.

Another object is to provide a device that will not interfere with the operation of the dispenser when it is desired not to use the said device.

Another object is to provide a regulating device to regulate the amount of liquid dispensed according to the rise and fall of the market.

A further object is to provide a purely mechanically operated device to permit locating the dispenser in places where it would be impractical to have an attendant and where electric current would not be available.

These and other objects will be apparent from the accompanying drawings and specification.

In the drawings—

Figure 1 is a horizontal section;

Figure 2 is a longitudinal vertical section;

Figure 3 is a transverse vertical section;

Figure 4 is a detail of the spring motor, the measuring drum and the governor;

Figure 5 is a detail of the regulating device;

Figure 6 is an enlarged detail of a push button, a bar and a section of a trip lever;

Figure 7 is a front end elevation.

In carrying out this invention I provide a housing 1 having a door 2 provided therein. A bearing support 4 is provided within the housing 1. A spring motor 5 is mounted upon a shaft 6 which is journaled in the bearing support 4 and in the wall of the housing 1. The said motor 5 has the inner end of its spring secured to the shaft 6 and the outer end to its drum 7. A spur gear 8 is rigidly secured to the shaft 6. A pinion 9 which meshes with the spur gear 8 is rigidly secured upon a pinion shaft 10 journaled in the bearing support 4. The said

pinion shaft 10 has its one end squared to provide means for engaging it with a crank. A ratchet 11 is rigidly secured upon the shaft 6, while a dog 12 which is pivotally secured to the bearing support 4 engages the said ratchet 11. Bearing supports 43 are provided within the housing 1 to provide means for journaling a drum shaft 13 therein. The said drum shaft 13 is also journaled to the bearing support 4. Idler shafts 14 and 15 and a governor shaft 16 are journaled to the bearing support 4 and the wall of the housing 1. A gear 17 is rigidly secured to the drum 7 of the spring motor 5. A gear 18 which is rigidly secured to the drum shaft 13, meshes with the gear 17 of the drum 7 and a pinion 19 which is rigidly secured to the idler shaft 14. A gear 20 which is rigidly secured to the idler shaft 14, meshes with a pinion 21 which is rigidly secured to the idler shaft 15. A gear 22 is rigidly secured to the idler shaft 15. The said gear 22 meshes with a pinion 23 which is rigidly secured to the governor shaft 16. The said pinion 23 has an extended hub 24. A disc 25 having an extended hub 26 is slidably secured to the governor shaft 16. A governor 27 is secured to the extended hub 24 of the pinion 23 and to the extended hub 26 of the disc 25. A regulating device 28 is mounted within the housing 1 above the governor 27. The said regulating device consists of an adjustment screw 29 journaled to brackets 30 which are secured to the top of the housing 1. Guide bars 31 are rigidly secured to the brackets 30. Combined adjustment and guide collars 32 are provided. The said combined adjustment and guide collars 32 engage the adjustment screw 29 and the guide bars 31. A shifting arm 33 which is rigidly secured to the combined adjustment and guide collars 32, engages the disc 25. A gauge plate 34 is mounted in front of the upper part of the combined adjustment and guide collars 32 in such a manner that the indicator 35 which is incorporated in the combined adjustment and guide collars 32, slidably engages the same. A measuring drum 36 is rigidly secured to the drum shaft 13. The said measuring drum 36 has a groove 37 cut transversely in its face. Measuring grooves 38, 39 and 40 are cut longitudinally in the face of the measuring drum 36. The said grooves 38, 39 and 40 originate in the transversely cut groove 37 and terminate in the

said transversely cut groove 37 at the beginning of the groove 38. The said groove 38 which is a trifle shallower than the groove 37, runs at an equal depth for a distance of three-fourths of the circumference where it becomes shallow and remains so until it terminates in the groove 37. The groove 39 is similar to the groove 38 with the exception that the said groove 39 becomes shallow at a distance of one-half of the circumference. The groove 40 is shallow for the full circumference after it has left the groove 37. A drum locking lever 41 carrying rollers 44 and 44' is secured to one of the end walls of the housing 1 through the medium of a knuckle joint. The said drum locking lever 41 which is secured above the measuring drum 36 and engages the same with an arm 42 carrying a roller 44, is formed into a quarter circle and a right angle in order to permit shifting means to engage the same. Trip levers 45, 46 and 47 which are adapted to engage the lever 41 are pivotally mounted upon a shaft 48 mounted upon supports 49. The trip levers 45, 46 and 47 are formed in such a manner that the pivoted portions thereof are in line with the respective grooves 38, 39 and 40. The lever 45 is directly underneath the lever 41, while the extreme ends of the levers 46 and 47 are bent and slightly inclined toward the drum locking lever 41 so as to engage and operate the drum locking lever 41 independently of each other in a very efficient manner as shown in Figures 1 and 2. Coin grooves 50 are provided in the said trip levers 45, 46 and 47. Coil springs 51 which are secured to the forward end of the trip levers 45, 46 and 47 and to the bottom of the housing 1, are provided; the said coil springs 51 being merely strong enough in order to balance the trip levers 45, 46 and 47 when in an inoperative position. A valve operating lever 52 having an arm 53 incorporated therein, is pivotally secured to an arm 54 incorporated in the bearing support 4. The said arm 53 engages the roller 44' of the drum locking lever 41. A secondary gasoline line 56 is mounted in the housing 1 and secured in the primary gasoline line 55. A valve 57 is located in the primary gasoline line 55 between the ends 58 of the secondary gasoline line 56. A ball and socket type valve 59 is located in the secondary gasoline line 56. A coil spring 60 which is secured within the secondary gasoline line 56, to the said secondary gasoline line 56 and the ball 61 of the ball and socket type valve 59, is adapted to keep the said ball 61 firmly seated in its socket 62. An eccentric 63 having an arm 64 incorporated therein, is journaled in the secondary gasoline line 56. The said arm 64 is formed at a slight angle to the vertical center line of the eccentric 63 and is pivotally secured to the valve operating lever 52 so that when the said lever 52 is raised, the arm 53 will be depressed causing the arm 64 to be turned downward through the pivotal relation with the said arm 53. A connecting rod 65 which is pivotally secured to the ball 61, is journaled to the eccentric 63. Coin slots 66, 67 and 68 having respective runways 69, 70 and 71, are provided. The said runways 69, 70 and 71 have magnets 72 mounted therein. Bars 73, 74 and 75 having respective coin slots 76, 77 and 78 provided therein, are mounted in the respective guides 79, 80 and 81 and have communication with the coin slots 66, 67 and 68 through the respective runways 69, 70 and 71. The coin slots 66 and 76, the runway 69, the bar 73 and the guide 79 are provided for the operation of the machine with a quarter of a dollar, while the coin slots 67 and 77, the runway 70, bar 74 and guide 80 are provided for the operation of the machine with a half of a dollar. The coin slots 68 and 78, the runway 71, bar 75 and guide 81 are provided for the operation of the machine with a dollar. The guides 79, 80 and 81 have apertures 82 and 83 provided therein, the apertures 82 being a trifle smaller than the coins used in the respective slots, while the apertures 83 are a trifle larger. The object of this arrangement is to prevent the operation of the machine with undersized coins or slugs. Any undersized coins or slugs that may be inserted into one of the coin slots 66, 67 and 68 are guided into the respective coin slot of one of the bars 73, 74 and 75 where they fall through the aperture 82 into the coin box 3 incorporated in the housing 1, while the correct coin will remain in the coin slot into which it had been guided until it is pushed over the aperture 83 where it will fall into the coin groove 50 of the trip lever located directly underneath the said aperture 83. Buttons 84 are secured to the bars 73, 74 and 75; the said buttons 84 being marked to show the denomination of the coin with which the respective bars operate. Springs 85 are secured to the bars 73, 74 and 75 and to the runways 69, 70 and 71 to provide means for retaining the normal position of the bars 73, 74 and 75 after the said bars have been operated.

In operation, the valve 57 in the primary gasoline line 55 is closed. The governor 27 which governs the speed of the spring motor 5, is regulated according to the rise and fall of the price of gasoline by means of the regulating device 28 which operates as follows: The screw 29 is turned until the indicator 35 of the guide collar 32 points to the current price of the liquid being dispensed, as for instance, eighteen, as shown on the gauge plate 34 in Figure 5. In thus setting the guide collar 32, the governor 27 is either expanded or contracted by means of the shifting arm 33 which engages the 125

governor disc 25, thus controlling the speed of the motor 5 in the well known manner. In order to operate the ball and socket type valve 59 a coin is inserted into one of the 5 coin slots 66, 67 and 68. A coin of the twenty-five cent denomination would be inserted into the coin slot 66 and pass through the runway 69 into the coin slot 76 of the bar 73. The button 84 of the said bar 73 10 is pressed forcing the bar 73 back until the coin slot 66 is in line with the aperture 83 of the guide 79, whereupon the coin will drop into the coin groove 50 of the trip lever 45, causing the said lever to overbalance, thus raising the drum locking lever 41 enough to permit the arm 42 to enter the groove 38 upon the rotation of the measuring drum 36. The coin rolls along in the coin groove 50 until the end of the said 15 trip lever 45, where it falls into the coin box 3. As long as the coin remains in the coin groove 50 of the trip lever 45, the drum locking lever 41 will remain in a raised position, thus giving the spring motor ample 20 time to get into motion in order to rotate the measuring drum 36. The ball and socket type valve 59 remains closed until the roller 44 of the arm 42 starts ascending the rise located in the groove 38 prior 25 to entering the shallow portion of the said groove 38. In ascending into the shallow portion of the groove 38, the roller 44' of the arm 43 comes into contact with the arm 53 of the valve operating lever 52, thus raising 30 the said arm 53 and turning the arm 64 of the eccentric 63 down. When the arm 64 of the eccentric 63 is turned down, the said eccentric 63 is turned, thus opening the ball and socket type valve 59 and permitting the 35 gasoline to pass through the said valve 59 into the regular glass container. The ball and socket type valve 59 remains open until the arm 42 drops back into the groove 37. Coins inserted into the coin slots 67 and 40 45 will operate the device in the same manner as above described except that the extreme ends of the levers 46 and 47 which are slightly inclined toward the drum locking lever 41 when raised will cause the said 45 drum locking lever 41 to slide in line with the respective groove of the drum 36, relative to the operated lever. In order to cut out the vending machine the valve 57 of the primary gasoline line 55 is opened up. 50 55 While I have herein described a certain specific method of constructing and assembling the elements of my invention, it is understood same may be varied in minor details, not departing from the spirit of my invention as defined in the appended claims. 60

1 claim:

1. In combination with a liquid dispenser a coin operating vending device comprising a housing; a drum operated spring motor 65 in said housing, said drum having a trans-

versely cut groove and longitudinally cut grooves having shallow portions varying in lengths corresponding with the value of the coin inserted; a locking lever engaging said transverse groove to keep the drum from rotating under the influence of the spring motor; a set of trip levers for releasing the locking lever which cause the said locking lever to follow one of the longitudinally cut grooves depending upon the particular trip lever operated by an inserted coin; a valve for dispensing liquid, the said valve being connected with and held open by the said locking lever for varying lengths of time, depending upon the length of the shallow portion of the particular groove in which the locking lever is travelling. 70 75 80 85 90 95 100 105

2. In a coin operated liquid dispenser, the combination of a drum operated spring motor, said drum having a transversely cut groove and longitudinally cut grooves having shallow portions varying in lengths corresponding to the value of the coin inserted; a locking lever engaging the transverse groove to keep the drum from rotating under the influence of the spring motor; a set of trip levers for releasing said locking lever which cause the said locking lever to follow one of the longitudinally cut grooves depending upon the particular trip lever operated by the inserted coin; a valve for dispensing liquid, the said valve being operated by said locking lever and being held open for varying lengths of time depending upon the length of the shallow portion of the particular groove in which the said locking lever is travelling; a governor regulated by an adjustable arm for controlling the speed of said spring motor in accordance with the value of the liquid being dispensed. 110 115 120 125 130

3. In a coin operated liquid dispenser, the combination of a drum operated spring motor, said drum having a transversely cut groove and longitudinally cut grooves having shallow portions varying in lengths corresponding to the value of the coin inserted; a locking lever engaging the transverse groove to keep the drum from rotating under the influence of the spring motor; a set of trip levers for releasing said locking lever which cause the said locking lever to follow one of the longitudinally cut grooves depending upon the particular trip lever operated by the inserted coin; a valve for dispensing liquid, the said valve being operated by said locking lever and being held open for varying lengths of time depending upon the length of the shallow portion of the particular groove in which the said locking lever is travelling; and means for regulating the speed of said motor in respect to the current value of the liquid being dispensed.

versely cut groove and longitudinally cut grooves having shallow portions varying in lengths corresponding with the value of the coin inserted; a locking lever engaging said 5 transverse groove to keep the drum from rotating under the influence of the spring motor; a set of trip levers for releasing the locking lever which cause the said locking lever to follow one of the longitudinally cut 10 grooves depending upon the particular trip

lever operated by an inserted coin; a valve for dispensing liquid; and means engaging said locking lever and said valve for holding open said valve for varying lengths of time depending upon the length of the shallow portion of the particular groove in which the locking lever travels.

In testimony whereof I affix my signature.

IRWIN WALDSMITH.
